United States Patent Office

Des. 184,732
Patented Mar. 31, 1959

184,732

HINGE

Don Heyer, El Monte, and James W. Maize, La Habra, Calif., assignors to M and H Industries, Inc., Los Angeles, Calif., a corporation of California

Application September 2, 1958, Serial No. 52,474

Term of patent 14 years

(Cl. D10—9)

Fig. 1 is a perspective view of a hinge showing our new design;

Fig. 2 is an end elevation thereof;

Fig. 3 is a rear elevation thereof;

Fig. 4 is a top plan view thereof; and

Fig. 5 is a sectional view taken on the line 5-5 of Fig. 3.

We claim:

The ornamental design for a hinge, as shown.
